UNITED STATES PATENT OFFICE.

WILLIAM MILLSPAUGH, OF MIDDLETOWN, NEW YORK.

DESIGN FOR SAW-HANDLE.

Specification forming part of Design No. **7,419**, dated May 5, 1874; application filed April 10, 1874.
[Term of Patent 7 years]

To all whom it may concern:

Be it known that I, WILLIAM MILLSPAUGH, of Middletown, in the county of Orange and State of New York, have invented certain new and useful Improvements in Design for Saw-Handles; and I do hereby declare that the following is a full, clear, and exact description thereof, which will enable others skilled in the art to which it pertains to make and use the same, reference being had to the accompanying drawings, and to the letters of reference marked thereon, which form a part of this specification.

My design relates to handles for saws, and

the nature thereof is fully illustrated in the accompanying drawing, which represents a side view of my saw-handle.

What I claim is—

The design for a saw-handle, as shown and described.

In testimony that I claim the foregoing as my own I affix my signature in presence of two witnesses.

WM. MILLSPAUGH.
